W. S. KINSLEY

APPARATUS FOR AND METHOD OF HANDLING FIBROUS TEXTILE STOCK.

Filed June 3 1922

Traverso: William S. Kisselby
by Emily Booth James & Nancy
Atkins

UNITED STATES PATENT OFFICE.

WILLIAM S. KINSLEY, OF READING, MASSACHUSETTS, ASSIGNEE TO THE RUSSELL COMPANY, OF BOSTON, MASSACHUSETTS, A CORPORATION OF MASSACHUSETTS.

APPARATUS FOR AND METHOD OF HANDLING FIBROUS TEXTILE STOCK.

Application filed June 3, 1923. Serial No. 565,782.

To all whom it may concern:

Be it known that I, WILLIAM S. KINSLEY, a citizen of the United States, and a resident of Reading, in the county of Middlesex and State of Massachusetts, have invented an Improvement in Apparatus for and Methods of Handling Fibrous Textile Stock, of which the following description, in connection with the accompanying drawings, is a specification, like characters on the drawings representing like parts.

My invention pertains to apparatus for and method of handling fibrous textile stock such as wool, shoddy, or the like, wherein the material is conveyed by means of a blast of air.

My invention has among its objects the provision of dividing the stock and the air in a simple and expeditious manner without necessitating a reduction in velocity of the air current. My invention, however, will be best understood from the following description when read in light of the accompanying drawings of one specific embodiment of my invention selected for illustrative purposes, while the scope of my invention will be more particularly pointed out in the appended claims.

In the drawings:—

Fig. 1 represents a vertical section through a bin for receiving wool or shoddy; and

Fig. 2 is a section on the line 2—2 of Fig. 1.

Referring to the drawings and to the preferred embodiment of my invention, I have shown a bin 1 having an end wall 3, the bottom wall 5 and top wall 7. Entering the bin is an air blast conduit 9 for conveying finished stock to the bin, the stock being blown through the conduit by a current of air, suitable means, not shown, being provided for creating the blast of air and for placing the stock in the conduit.

Heretofore, it has been necessary, in order to separate the stock from the air to reduce the velocity of the air flow by expansion in order that the material will drop into the bottom of the bin without the air affecting it. My present invention has to do with effecting this separation without the employment of the cumbersome and bulky apparatus and arrangement of conduits heretofore employed for effecting this result in prior devices known to me.

To the above ends the conduit 9 terminates within a box having an open bottom and a foraminous wall opposite the end of the conduit. When the air strikes the foraminous wall the material falls to the bottom of the bin while the air passes through the foraminous wall and is discharged from the bin through a second foraminous wall. Referring to the drawings, which disclose the specific embodiment of my invention selected for illustration, the box just referred to comprises the end walls 11 and 13 and the side walls 15, all of which are formed of screen held in suitable framing 17 which is suspended from the top wall 7 of the bin in any suitable manner. To improve the separating operation the walls 15 taper toward the open bottom 19 of the box, while to prevent the stock from being held by the blast against the wall 13 opposite the end of the conduit and accumulating there, said wall at this point is provided with an imperforate baffle 21. Further, the wall 3 of the bin is provided with an opening closed by the screen 23 and aligned with the conduit 9.

In operation the stock conveyed by the blast of air as heretofore explained falls gently through the bottom of the box to the bottom bin, while the air passes in the direction of the arrows across the top of the bin through the screens 13 and 23 without disturbing the material in the bottom of the bin.

Although I have described for purposes of illustration one specific embodiment of my invention, it is to be understood that I am not limited thereby to its particular mechanical details but that wide deviations may be made therefrom without departing from the spirit of my invention.

Claims:

1. In an apparatus of the character described, a bin for receiving fibrous textile stock, an air blast conduit for such material terminating within said bin, a foraminous wall in front of the end of said conduit, and the wall of said bin having a foraminous portion aligned with the first mentioned wall.

2. In an apparatus of the character described, a bin for receiving fibrous textile stock, an air blast conduit for such material terminating within said bin, a foraminous

wall in front of the end of said conduit, and the wall of said bin having an opening aligned with said foraminous wall.

3. In an apparatus of the character described, a bin for receiving fibrous textile stock, a box of foraminous material having a wall with an opening and having an open bottom spaced above the bottom of said bin, an air blast conduit for said material terminating at said opening, and the wall of said bin having a foraminous portion spaced from and aligned with the opposite wall of said box.

4. In an apparatus of the character described, a bin for receiving fibrous textile stock, an air blast conduit for said material arranged to have its discharge projected across said bin above the bottom of said bin, an opening in the wall of said bin aligned with the end of said conduit, and a foraminous wall interposed between the end of said conduit and said opening.

5. In an apparatus of the character described, a bin for receiving fibrous textile stock, an air blast conduit for said material arranged to have its discharge projected across said bin above the bottom of said bin, an opening in the wall of said bin having a foraminous closure aligned with the end of said conduit, and a foraminous wall interposed between the end of said conduit and said opening.

6. In an apparatus of the character described, a bin for receiving fibrous textile stock, an air blast conduit for said material arranged to have its discharge projected across said bin above the bottom thereof and having its end spaced from the wall of said bin toward which it discharges, a baffle in spaced relation with the end of said conduit, a foraminous wall adjacent said baffle, and the wall of said bin toward which the conduit discharges having a foraminous portion aligned with the first mentioned foraminous wall.

7. In an apparatus of the character described, a bin for receiving fibrous textile stock, a box of foraminous material having an open bottom spaced above the bottom of said bin, an air blast conduit for said material terminating at an opening in one wall of said box, a baffle aligned with the end of said conduit, and the wall of said bin having a foraminous portion aligned with the opposite wall of said box.

8. In an apparatus of the character described, a bin for receiving fibrous textile stock, a box having a bottom with a restricted opening, an air blast conduit for said material discharging into said box above its bottom, the wall of said box opposite the end of said conduit being forami-

nous, and the wall of said bin opposite the end of said conduit having a foraminous portion aligned with said conduit.

65

9. In an apparatus of the character described, a bin for receiving fibrous textile stock, a box having an open bottom and side walls tapering toward said bottom, an air blast conduit entering a wall of said box and projecting its discharge across said box above the bottom thereof, the wall of said box toward which said blast travels being foraminous, and the portion of the wall of said bin toward which the blast travels being foraminous.

70

10. In an apparatus of the character described, a bin for receiving fibrous textile stock, a box having an open bottom and side walls tapering toward said bottom, an air blast conduit entering a wall of said box and projecting its discharge across said box above the bottom thereof, the wall of said box toward which said blast travels being foraminous, a baffle disposed between the end of said conduit and the last mentioned wall, and the portion of the wall of said bin toward which the blast travels being foraminous.

80

11. In an apparatus of the character described, an air blast conduit for conveying fibrous textile stock, a box into which said conduit opens, said box having an open bottom and side walls of foraminous material tapering toward said bottom, and the wall of said box opposite the end of said conduit being foraminous and having a baffle aligned with the end of said conduit.

90

12. The method of separating fibrous textile stock from a high velocity current of air and depositing said material in a bin which consists in projecting said blast across the top of said bin through a succession of spaced upright screens.

100

13. The method of separating fibrous textile stock from a high velocity current of air which consists in projecting said air to cause it to travel in a horizontal direction through a succession of spaced upright screens.

105

14. The combination with a bin or the like for receiving fibrous textile stock, of an air blast conduit for conveying said material, a box into which said air blast conduit discharges mixed fibrous stock and air in a substantially horizontal direction, said box having an open bottom through which said fibrous stock may fall into said bin, and said box having means for screening said fibrous stock from the air conveying it.

115

In testimony whereof, I have signed my name to this specification.

120

WILLIAM S. KINSLEY.
